UNITED STATES PATENT OFFICE.

FRANK M. MURRAY, OF CADYVILLE, NEW YORK.

INTERNAL-COMBUSTION ENGINE.

1,256,720.

Specification of Letters Patent. Patented Feb. 19, 1918.

Application filed March 8, 1917. Serial No. 153,482.

To all whom it may concern:

Be it known that I, FRANK M. MURRAY, a citizen of the United States, residing at Cadyville, in the county of Clinton and State of New York, have invented certain new and useful Improvements in Internal-Combustion Engines, of which the following is a specification, reference being had to the accompanying drawings.

- 10 This invention relates to certain improvements in internal combustion engines and it is an object of the invention to provide a novel and improved device of this general character including a slide valve for controlling the intake and the exhaust and which valve operates with a minimum of frictional resistance and which also eliminates the use of a valve of the "puppet" type.
- 20 It is also an object of the invention to provide a device of this general character including a novel and improved slide valve for controlling the intake and the exhaust and which valve includes a positively operated member coacting with both the intake and the exhaust together with a supplemental member coacting with the intake alone and operated under the influence of the first named member.
- 30 The invention consists in the details of construction and in the combination and arrangement of the several parts of my improved internal combustion engine whereby certain important advantages are attained and the device is rendered simpler, less expensive and otherwise more convenient and advantageous for use, all as will be herein-after more fully set forth.

The novel features of the invention will 40 hereinafter be definitely claimed.

In order that my invention may be the better understood, I will now proceed to describe the same with reference to the accompanying drawings, wherein—

45 Figure 1 is a fragmentary view partly in section and partly in elevation of a motor of a four cycle type constructed in accordance with an embodiment of my invention;

50 Fig. 2 is a view in top plan of the device as disclosed in Fig. 1 with the top plate and

spark plug removed and with certain of the parts disclosed in Fig. 1 omitted for clarity in disclosure;

Fig. 3 is a view in plan of the division or stationary plate as herein employed in connection with my improved valve; 55

Fig. 4 is a view in top plan of the supplemental member employed in my improved valve as herein disclosed;

Fig. 5 is a fragmentary view in top plan 60 of my improved motor with the top plate and main member of my improved valve removed, the supplemental member of the valve being shown in a second position or at its position during the exhaust stroke of the 65 piston;

Fig. 6 is a fragmentary sectional view taken substantially on the line 6—6 of Fig. 2; and

Fig. 7 is a view partly in elevation and 70 partly in section illustrating an internal combustion engine constructed in accordance with a further embodiment of my invention.

As disclosed in the accompanying drawings, 1 denotes the cylinder of an internal 75 combustion engine having its opposite ends open and in which works the piston 2 operatively engaged through the medium of the rod 3 with the crank 4. The crank 4 is positioned within the casing 5 and to which 80 casing is secured an end portion of the cylinder 1.

It is to be particularly noted that the rod 3 is engaged with the crank 4 through the medium of the removable block 6 held to the 85 rod by the bolts 7 with which coat the nuts 8 or other removable clamping members. A side wall of the casing 5 is provided with a hand opening 9 normally closed by the plate 90 or the like.

It is to be noted that the opening 9 is so positioned as to permit convenient access to the block 6 so that said block can be easily applied or removed as the necessities of practice may require. This operation is facilitated in view of the fact that the bolts 7 are disposed transversely through the rod 3. It is also thought to be self-evident that after the rod 3 has been disconnected from the 95 crank 4, the piston 2 may be readily with- 100

drawn through the outer end of the cylinder 1. It will also be self-evident that the piston 2 may be readily inserted within the cylinder 1 and operatively engaged with the 5 crank 4 by a reverse operation.

Coacting with the outer end of the cylinder 1 is the removable head H preferably cast and provided with the water jacket 11 in communication with the water jacket 12 10 of the cylinder 1. The head H is also provided with the intake port 14 and the exhaust port 15, said ports being in communication with the conical chamber 16 formed in the inner face of the head H. The head 15 H is adapted to snugly fit within the cylinder 1 and is provided with an outstanding annular flange 17 resting upon the upper edge of the cylinder 1 and interposed between the upper edge of the cylinder 1 and 20 the annular flange 17 is a gasket 18 for a purpose which is believed to be self-evident. It is also to be understood that the periphery of the portion of the head H seating within the cylinder 1 is machined so that 25 the same will fit tightly within the cylinder 1 yet permit the head to be removed.

The top or outer face of the head H is flat and preferably machined and extending across the top or flat face of the head H is 30 a groove or channel 19 having one end portion of greater depth, as indicated at 20. The intake port 14 is in communication with the portion 20 of the groove, while the exhaust port 15 is in communication with the 35 opposite end portion of the groove.

Resting upon the base of the groove 19 is a plate 21. The plate 21 extends the entire length of the groove 19 and overlies the portion 20 of the groove. This plate 21 serves 40 as a wear plate and also as a division plate as will hereinafter be more particularly set forth.

An intermediate portion of the plate 21 is provided with the opening 22 through 45 which is directed the spark plug S when said plug is in applied position. By this means the plug S serves to hold the plate 21 in applied position and against longitudinal movement.

50 As is particularly disclosed in Fig. 1 the spark plug S extends through the head H at the apex of the conical chamber 16.

The plate 21 is provided with the ports 14^a and 15^a in alignment or register with the 55 ports 14 and 15 respectively.

Also positioned within the groove 19 and resting upon the plate 21 is a slide member 23 of a length in excess of the length of the groove 19 so that one end portion of the 60 member 23 extends beyond a side of the head H. The extended portion of the member 23 is provided with the recess or slot 24 through which extends the upper end por-

tion of the vertically disposed rocker arm 25. The upper or free end portion of the 65 arm 25 also extends between the rollers 26 or other anti-friction members carried by the extended portion of the member 23.

The member 23 is provided with the ports 14^b and 15^b adapted to coact with the ports 70 14 and 15 in a manner to be hereinafter more particularly set forth, and in order that the requisite endwise movement may be imparted to the member 23, said member is provided at a point intermediate the ports 75 14^b and 15^b with the longitudinally disposed slot 27 through which the spark plug S is directed.

Seated within the portion 20 of the groove 19 and resting upon the base thereof and 80 underlying the plate 21 is a supplemental slide member 28. The supplemental member 28 is provided with a port 14^c adapted to coact with the port 14 as will also be hereinafter more particularly set forth.

The outer end portion of the member 28 is provided with the slot 29 in which extends the free end portion of the pin 30 depending from the adjacent end portion of the member 23. The slot 29 is of a length equal 90 to the width of the port 14 plus the diameter of the pin 30 whereby it will be perceived that upon certain of the strokes of the piston 2, namely, compression stroke and exhaust stroke, the member 28 will be idle during the final half of each of said strokes so that the port 14 will be closed by the member 28 during the final half of either the compression stroke or exhaust stroke of the piston 2.

The movement of the member 23 under the influence of the arm 25 is equal to four times the width of the port 14 or 15, it being understood that said ports 14 and 15 are of equal width.

As illustrated in Fig. 1, the piston 2 has completed the first half of its intake stroke. Upon the completion of the intake stroke the wall α of the port 14^b will be in the position as indicated by dotted lines at a . Upon the compression stroke the wall α will move to the position indicated by dotted lines at b and back to the position a . Upon the return movement of the member 23 as effected by the last half of the compression stroke 115 the member 28 will remain stationary as permitted by the slot 29 and the pin 30 will assume a position at the end of said slot 29 opposite to that shown in Fig. 1. Upon the firing stroke the wall α will assume the position at c but the port 14 will be maintained closed by the member 28 as the port 14^b passes over the port 14^a in view of the fact that the member 28 or more particularly the port 14^c thereof is in one position rearwardly of the port 14^b. Upon the exhaust 120 125

stroke the wall α of the port 14^a will move to the position as indicated by dotted lines at d and then back to c . This movement brings the port 14^a of the member 28 in register with the port 14.

5 Detachably engaged with the outer or flat face of the head H is the removable plate 31 provided with the ports 14^a and 15^a in alignment or register with the ports 14 and 15 respectively. The plate 21 is provided with an open slot 32 through which the pin 30 is disposed.

It will be self-evident that the plate 21 maintains the members 23 and 28 in separated relation so that the movement of the member 28 depends entirely upon the pin 30 carried by the member 23. It is also to be observed that the plate 21 is provided with the openings 33 through which oil or 10 the like is adapted to pass in order that the member 28 may also be lubricated. The oil may be applied in any manner which best meets the requirements of practice.

In order that the member 28 may be positively held against movement during its idle period, I provide an edge of the member 28 with the suitably spaced notches or recesses 34 adapted to receive a protuberance 35 carried by the spring member 36 mounted with 20 in a suitable recess 37 formed in the adjacent side wall of the portion 20 of the groove 19. At this time I wish to state that I do not desire to limit myself to the exact form of spring 36 or protuberance 35 as any yieldable or resilient means may be employed for 25 positively holding the member 28 against movement which will operate with convenience and facility.

As is illustrated in Fig. 1, the rocker arm 25 extends within the casing 5 and has its lower end bifurcated, as at 38, to straddle the eccentric shaft 39. The shaft 39 is operatively engaged, as indicated at 40, with the crank shaft 41, and said shafts 39 and 45 41 rotate in a ratio of 1 to 2 for a purpose which is believed to be self-evident. It is also to be noted that the eccentric shaft 39 serves to move the upper free end portion of the arm 25 a distance equal to four times the 50 width of the port 14 or 15.

In the embodiment of my invention as illustrated in Fig. 7 of the accompanying drawings, I disclose a construction which may be readily applied to internal combustion engines already in use and particularly 55 where the port communicating with the cylinder is arranged in a side thereof.

As disclosed in Fig. 7, the cylinder 1^a is provided adjacent its upper end with the 60 port 42 over which is disposed the plate 43 provided with the intake port 44 and the exhaust port 45. The outer face of the plate 43 is provided with a suitable groove

46 in which is mounted the slide member 23^a and the supplemental member 28^a. The member 23^a is provided with the ports 44^a and 45^a adapted to coact with the ports 44 and 45 respectively, while the supplemental or auxiliary member 28^a is provided with the port 44^b adapted to coact with the port 44. 70

The members 23^a and 28^a are provided with the coacting pin 30^a and slot 29^a operating in a manner and for the purpose as has been hereinbefore particularly set forth relative to the members 23 and 28. The members 23^a and 28^a have also interposed therebetween the plate 21^a for a purpose which is believed to be self-evident in view of what has hereinbefore been set forth relative to the plate 21. 80

The auxiliary or supplemental member 28^a is also adapted to be maintained in its idle positions in the same manner as has been described relative to the member 28. In fact it is to be stated that the construction and operation of the controlling means for the ports 44 and 45 is substantially the same as has hereinbefore been disclosed relative to the ports 14 and 15. 85

The members 23 and 28 are maintained in applied position through the medium of the removable plate 31^a. The upper end portion of the groove 46 is closed by the removable plate 47 which is provided with an oil cup 48 discharging upon the members 23^a and 28^a so that the same may be properly lubricated. The plate 47 also serves to maintain the plate 21^a against endwise movement as is thought to be clearly disclosed in Fig. 7.

The lower or extended portion of the member 23^a has detachably engaged therewith, as at 49, the rod 50. The rod 50 extends within the casing 5^a and is operatively engaged with the eccentric shaft 39^a whereby the requisite movement is imparted to the members 23^a and 28^a. It is also preferred that the rod 50 extend through the elongated upstanding bearing 51 carried by the casing 5^a so that said rod 50 is maintained in a fixed path of travel. It is also to be understood that the eccentric shaft 39 is adapted to be rotated relative to the crank shaft 41^a in a ratio of 1 to 2. 100

From the foregoing description, it is thought to be obvious that an internal combustion engine constructed in accordance with my invention is of an extremely simple and comparatively inexpensive nature and is particularly well adapted for use by reason of the convenience and facility with 115 which it may be assembled, and it will also be obvious that my invention is susceptible of some change and modification without material departure from the principles and spirit thereof and for this reason I do not 120 wish to be understood as limiting myself to 125

the precise arrangement and formation of the several parts herein shown in carrying out my invention in practice, except as hereinafter claimed.

5 I claim:

1. An internal combustion engine including a cylinder provided with an intake port and with an exhaust port, a piston within the cylinder, a slide member provided with 10 ports adapted to be brought into operative relation with said intake and exhaust ports, a supplemental slide member provided with a port adapted to coact with the intake port of the cylinder, means for imparting movement to the first named slide member, coacting means carried by both of the sliding members whereby the same are caused to move in unison during certain periods of the movement of the first named slide member, and a spring member co-acting with the supplemental slide member for positively holding the same against movement during its periods of idleness.
2. An internal combustion engine including a cylinder provided with an intake port and with an exhaust port, a piston within the cylinder, a slide member provided with 25 ports adapted to be brought into operative relation with said intake and exhaust ports, a supplemental slide member provided with a port adapted to coact with the intake port of the cylinder, means for imparting movement to the first named slide member, co-acting means carried by both of the sliding members whereby the same are caused to move in unison during certain periods of the movement of the first named slide member, and a spring positioned within the recess in the wall of the groove and co-acting 30 with the supplemental slide member for holding the supplemental slide member against movement during its periods of idleness.
3. An internal combustion engine including a cylinder provided with an intake port and with an exhaust port, a piston within the 35 cylinder, a slide member provided with ports adapted to be brought into operative relation with said intake and exhaust ports, a supplemental slide member provided with a port adapted to coact with the intake port of the cylinder, means for imparting movement to the first named slide member, co-acting means carried by both of the sliding members whereby the same are caused to move in unison during certain periods of the movement of the first named slide member, and means co-acting with the supplemental 40 slide member for positively holding the supplemental slide member against movement during its periods of idleness.

3. An internal combustion engine including a cylinder provided with an intake port and with an exhaust port, a piston within the 45 cylinder, a slide member provided with ports adapted to be brought into operative relation with said intake and exhaust ports, a supplemental slide member provided with a port adapted to coact with the intake port of the cylinder, means for imparting movement to the first named slide member, co-acting means carried by both of the sliding members whereby the same are caused to move in unison during certain periods of the movement of the first named slide members, and means for maintaining the slide members in separated relation.

4. An internal combustion engine including a cylinder provided with an intake port and with an exhaust port, a piston within the 60 cylinder, a slide member provided with ports adapted to be brought into operative relation with said intake and exhaust ports,

a supplemental slide member provided with a port adapted to coact with the intake port 65 of the cylinder, means for imparting movement to the first named slide member, said supplemental slide being provided with a slot disposed in the same direction as the direction of travel of the member, and a 70 part carried by the first named slide member extending within the slot of the supplemental slide member, the slot in the supplemental slide member being of a length equal to the width of the intake port plus a diameter of the part within the slot.

5. An internal combustion engine including a cylinder provided with an intake port and an exhaust port, the portion of the cylinder provided with said ports being provided with a groove in communication with the ports, a wall of said groove being provided with a recess, a piston within the cylinder, a slide member provided with ports adapted to be brought into operative 85 relation with said intake and exhaust ports, a supplemental slide member provided with a port adapted to co-act with the intake port of the cylinder, means for imparting movement to the first named slide member, co-acting means carried by both of the sliding members whereby the same are caused to move in unison during certain periods of the movement of the first named slide member, and a spring positioned within the recess in the wall of the groove and co-acting 90 with the supplemental slide member for holding the supplemental slide member against movement during its periods of idleness.

6. An internal combustion engine including a cylinder provided with an intake port and with an exhaust port, a piston within the cylinder, a slide member provided with 100 ports adapted to be brought into operative relation with said intake and exhaust ports, a supplemental slide member provided with a port adapted to co-act with the intake port of the cylinder, a movable arm operatively engaged with the slide member, an eccentric 110 shaft rotated by the piston, a portion of the movable arm straddling said eccentric shaft, and co-acting means carried by both of the sliding members whereby the same are caused to move in unison during certain 115 periods of the movement of the first named slide member.

7. An internal combustion engine including a cylinder provided with an intake port and with an exhaust port, a piston within 120 the cylinder, a slide member provided with ports adapted to be brought into operative relation with said intake and exhaust ports, a supplemental slide member provided with a port adapted to co-act with the intake 125 port of the cylinder, a movable arm oper-

atively engaged with the slide member, an eccentric shaft rotated by the piston, a portion of the movable arm straddling said eccentric shaft, and co-acting means carried by both of the sliding members whereby the same are caused to move in unison during certain periods of the movement of the first named slide member, said eccentric shaft serving to move the slide member a distance

equal to four times the width of the intake 10 port or exhaust port.

In testimony whereof I hereunto affix my signature in the presence of two witnesses.

FRANK M. MURRAY.
